[57] CLAIM

The ornamental design for a sprayer or similar article, substantially as shown and described.

DESCRIPTION

FIG. 1 is a perspective view taken from the front and right side of a sprayer or similar article showing my new design;

FIG. 2 is a perspective view taken from the rear and left side thereof;

FIG. 3 is a front perspective view of a modified form of the sprayer or similar article shown in FIG. 1;

FIG. 4 is a front perspective view of a second modified form of the sprayer or similar article shown in FIG. 1; and

FIG. 5 is a front perspective view of a third modified form of the sprayer or similar article shown in FIG. 1.

FIG.1

FIG.2

FIG. 3

FIG. 4

FIG. 5
